UNITED STATES PATENT OFFICE.

BERT E. LAMKIN, OF SPRINGFIELD, ILLINOIS, ASSIGNOR OF ONE-HALF TO ROBERT G. OSTEN, OF SPRINGFIELD, ILLINOIS.

HOBBY-HORSE VELOCIPED.

1,090,550.

Specification of Letters Patent. Patented Mar. 17, 1914.

Application filed July 21, 1913. Serial No. 780,247.

To all whom it may concern:

Be it known that I, BERT E. LAMKIN, a citizen of the United States, residing at Springfield, in the county of Sangamon and 5 State of Illinois, have invented a new and useful Hobby-Horse Velocipede, of which the following is a specification.

The present invention appertains generally to velocipedes, and relates more particularly to a vehicle of the hobby horse type.

It is the object of the present invention to provide a body, preferably of the configuration of a horse or other animal, mounted for 15 rocking movements upon a carriage or truck, and operatively connected with the running gear of the carriage, in order that the motion imparted to the body, or horse, will propel the vehicle, and in order that 20 the body, or horse, will simulate the movements of a live animal.

Another object of the present invention is to provide an appliance of the nature indicated wherein the rocking body or horse, 25 which the occupant is adapted to ride, is connected to the crank of the rear or driving axle, by means of a pitman, novel means being provided, and being actuated by the body or horse, for throwing the pitman past 30 dead center at the ends of its strokes.

A further object of the present invention is to provide novel means whereby the rider or occupant may conveniently steer or guide the vehicle.

35 It is also within the scope of the present invention to improve generally the construction and utility of devices of that character to which the present invention relates, in order that the present device shall be comparatively simple, substantial, and inexpensive in construction, as well as convenient and efficient in its use.

With the foregoing general objects outlined, and with other objects in view, which 45 will be apparent as the nature of the invention is better understood, the present invention resides in the combination and arrangement of parts and in the details of construction hereinafter described and 50 claimed, it being understood that changes in the precise embodiment of the invention herein disclosed, can be made within the scope of what is claimed, without departing from the spirit of the invention.

55 The invention has been illustrated in its

preferred embodiments in the accompanying drawings, wherein:

Figure 1 is a side elevation of the device. Fig. 2 is a sectional view taken approximately on the line 2—2 of Fig. 1, and illustrating the carriage or truck. Fig. 3 is a side elevation, parts being broken away, and parts being shown in section, the section being taken on the line 3—3 of Fig. 2. Fig. 4 is a cross section of the device, taken approximately on the line 4—4 of Fig. 1. Fig. 5 is a vertical section of a modified form of the device. Fig. 6 is a plan view of the modified form, with the body removed, parts being shown in section, and parts being broken away.

In carrying out the present invention, there is provided a suitable carriage or truck, designated generally by the numeral 1, and embodying a frame 2. The frame 2 is 75 preferably bent from a bar or length of stock 3, the bar 3 being doubled, and having its bend formed into an eye 4. The end portions 5 of the bar 3 are offset away from each other, or spread, in the manner of a fork, and the body 6 of the fork, or the forward portion of the frame, is offset upwardly, so as to elevate the eye or bearing 4 above the plane of the end portions 5. The abutting portions of the bar 3 adjoining the eye 4 are preferably riveted or otherwise secured together for the purpose of rigidity.

The rear or driving axle 7 is journaled through the ends of the bar 3, or through the rear end of the frame 2, and has the 90 rear driving or propelling wheels 8 secured upon its ends. The rear axle 7 is provided with a crank 9 intermediate the side portions 5 of the frame 2, the crank 9 being preferably set slightly to one side of the median plane or central line, of the frame 2.

A steering post 10 has its upper end journaled within the eye or bearing 4, and is provided at its lower end with a fork 11, in which the steering wheel 12 is journaled. 100 The fork 11, or the steering post, is provided with the laterally projecting arms 13 for controlling the swinging movements of the steering post, as will hereinafter more fully appear.

A standard or pedestal 14 is carried by the central portion of the frame 2, the lower end of the standard or pedestal 14 being preferably secured to a cross bar 14' terminally secured to the bar 3 adjoining its crotch. 110

Upon the standard or pedestal 14 is fulcrumed or pivoted the body 15, which is preferably of the configuration of a horse, or other animal, and which is provided with 5 the saddle or seat 16 upon which the occupant or rider is adapted to sit with his legs straddling the horse 15. The body or horse 15 is preferably hollow, and is provided with the lower opening 17 receiving the upper 10 per end of the standard 14. A cross pin 18 is terminally secured to the sides of the body 15 intermediate its ends, and adjoining the bottom of the body, the pin or rod 18 being journaled through the upper end of 15 the standard 14 to fulcrum or pivot the body 15 upon the standard. It will thus be apparent that the body 15 is disposed for rocking movements upon the carriage or truck, similar to an ordinary hobby horse.

20 In order that the rider or occupant of the body 15 may conveniently control the steering post 10, flexible actuating cords 19 are attached to the respective arms 13, and extend to the lower portion of the standard 14, 25 the standard 14 being provided with upper and lower guides or eyes 20 through which the cords 19 are threaded upwardly. The body 15 is provided with the apertures 21 in its sides slightly in advance of the fulcrum pin 18, the free ends of the cords 19 being 30 passed outwardly through the apertures 21 and having stirrups 22 attached thereto. The occupant or rider seated upon the saddle or seat 16 may conveniently insert his 35 feet into the stirrups 22, and by properly moving the stirrups up and down, the steering post 10 may be turned at will, so as to steer or guide the device over the surface traversed. The actuating cords 19 passing 40 through the apertures 21 adjoining the fulcrum point of the body, will eliminate any great variation in the position of the stirrups with respect to the body 15 under the varying conditions. It is also to be understood, 45 that the actuating cords 19 may be controlled by hand, if so desired, although the head of the horse 15 is preferably equipped with a halter having reins to be held in the hand or hands, while the feet are 50 engaged to the stirrups 22 to steer the device.

The rear portion of the body 15 is operatively connected with the rear running gear of the carriage or truck, a cross pin or rod 55 23 being engaged through the sides of the body 15 adjoining the rear end, or rear legs of the body, and a pitman or connecting rod 24 being engaged loosely at its upper end with the pin 23, and being engaged at its 60 lower end to the crank 9. In this manner, the rocking motion of the body 15 will impart a rotatory motion to the rear driving axle, in order that the device may be conveniently propelled by the rocking motion 65 imparted to the body or horse 15.

In order to throw the pitman or connecting rod 24 beyond dead center at the respective ends of its strokes, there has been provided the following mechanism: The standard 14 is provided intermediate its ends with 70 an opening 25 extending from its front side to its rear side, and a rocking shaft 26 is journaled through the standard 14 within the opening 25, and is provided at one end with a crank 27. A sheave or pulley 29 is secured upon the shaft 26 within the opening 25, and a cord or flexible element 30 is trained over the sheave 29 and is attached thereto, in order that when the cord 30 is moved, the sheave 29 will be partially rotated or rocked. The rear end of the cord 30 is attached to a cross pin 31 terminally secured to the sides of the body 15 adjoining its rear end, or between the rear legs, while the forward end of the cord 30 is attached to 75 a similar pin 32 terminally secured to the sides of the body 15 adjoining its forward end, or between the front legs. The front end of the cord 30 is preferably adjustably connected with the respective cross pin 32, and to this end, a threaded rod 33 is attached to the forward end of the cord 30, and bears a nut 34, a hook 35 engaging the pin 32 and loosely embracing the rod 33 under the nut 34, so that when the nut is tightened, the slack will be taken out of the cord 30, so as 80 to hold the cord taut. 90

A supplemental or secondary pitman or connecting rod 36 is connected with the crank 27 and is operatively connected with 100 the main or primary pitman 24. The pitman 36 embodies a tubular casing 37 having the upper and lower longitudinal slots 38 through which the pitman 24 passes. The pitman 24 carries pins or lugs 39 above and 105 below the casing 37, in order to maintain the casing in position upon the pitman 24, and to permit the casing 25, or the pitman 36, to oscillate or move sufficiently relative to the pitman 24. A coiled wire spring 40 is 110 housed within each end portion of the casing 37, the remote ends of the springs 40 seating against the ends of the casing 37, which are closed, and the adjoining ends of the springs seating against the opposite 115 edges of the pitman 24. The tension of one spring 40 equalizes or neutralizes the tension of the other spring, under normal conditions, that is, when the pitman 24 is intermediate its two dead centers. The pitman 120 36 further includes a threaded rod or stem 41 engaging the respective end of the casing 37 and pivotally or loosely engaging the crank 27. It will be evident that the stem 41 and tubular casing 37 may be adjusted 125 relative to each other, in order to properly position the casing 37 with respect to the main pitman 24, so that the proper operation will ensue. After the extensible or adjustable pitman 36 has been set and applied to 130

the device, the pitman 24 in passing through the casing 37 will lock the said casing from rotating with respect to the stem 41, the said stem being so connected with the crank 27, 5 as to prevent it from turning with respect to the casing 37.

In use, the rider or occupant sits astride the body or horse 15, with his feet engaging the stirrups 22 to control the steering post 10 or steering wheel, as above described. The rider or occupant then imparts a rocking or oscillatory movement to the body or horse 15, which will transmit a rotatory movement to the rear driving axle, so as to propel the 15 device. The body or horse 15 being rocked and propelled, will somewhat simulate the movements of a live animal, to the enjoyment of the rider.

One of the cardinal or salient features of 20 the present invention resides in the fact that when the actuating pitman 24 reaches its points of 'dead center, the same will be thrown beyond dead center, in order that the device may not become locked. This result 25 is accomplished in the following manner: Supposing the rear portion of the body 15 to be elevated, as seen in Fig. 1, when the rear portion of the body is depressed, the pitman 24 will move downwardly to the position illustrated in Fig. 3. During the depression or descent of the rear portion of the body 15, the cord 30 will have been moved forwardly, with respect to the standard 14, and consequently, the rocking shaft 30 26 will have been turned clockwise, as seen in Figs. 1 and 3, so as to throw the crank 27 rearwardly. The crank 27 being thrown rearwardly will force the forward spring 40 against the pitman 24, the tension of the 40 forward spring serving to throw the pitman 24 beyond dead center at the lower end of its downward stroke. The forward end of the body 15 is then depressed, the rear portion of the body rising, and the pitman 24 45 moving upwardly. When the rear portion of the body 15 is moved upwardly, the cord 30 will be drawn rearwardly, and the crank 27 will be thrown forwardly, so as to press the rear spring 40 against the pitman 24, and consequently, the tension created by the 50 rear spring 40, will throw the pitman 24 beyond dead center at the upper end of its stroke. Thus, as the body 15 is oscillated or rocked, there will be no liability for the device to become locked, at the two points of 55 dead center, and a continuous and easy movement of the device is therefore accomplished. The present device will operate lightly and easily, so as to obtain a comparatively high velocity or speed, with a 60 minimum expenditure of force, on the part of the operator or occupant.

In the variation illustrated in Figs. 5 and 6, the pin 18 is secured rigidly to the body 55 15 so as to oscillate therewith, the pin 18

being in the form of a rock shaft; and a segmental gear 30' is keyed or secured to the pin or rock shaft 18 and intermeshes with a pinion 29' keyed or secured on the rock shaft 26. Thus, the rock shaft 26 is made 70 to oscillate with the body 15 in a positive manner, and in a manner more simple than that above described. In this form, the standard 14^a is provided with an opening 25' extending from the upper end of the standard to a point below the pinion 29', or the standard 14^a may be of two parts, in order to permit the gears 29' and 30' to operate within the standard. Another alteration depicted in Figs. 5 and 6, resides in the driving 75 gear employed. In this form, there is provided a shaft 42 journaled through the side members 5 in advance of the rear axle 7', the shaft 42 being provided with a crank 9' with which the pitman 24' is connected, and a relatively large spur gear 43 being keyed or secured upon the shaft 42 and intermeshing with a pinion or relatively small spur gear 44 keyed or secured upon the rear axle 7'. In this manner, a relatively slow oscillation 80 of the body 15 will impart a relatively high velocity to the rear axle, in order that the velocipede may be driven at a greater speed, or with greater ease. Otherwise, the construction illustrated in Figs. 5 and 6, is 85 the same as that illustrated in the other figures, it being understood that the changes illustrated in Figs. 5 and 6, as well as others, may be utilized in the present device, without departing from the spirit of the invention as defined in the appended claims. 90

Having thus described the invention, what is claimed as new is:—

1. In a device of the character described, a wheel mounted carriage embodying a driving crank, a body mounted for rocking movements upon the carriage, a pitman connecting the said body and crank, and means operated by the said body and operatively connected to the said pitman for throwing 105 the same beyond its points of dead center.

2. In a device of the character described, a wheel mounted carriage including a driving crank, a body mounted for rocking movements upon the carriage, a pitman connecting the body and crank, a reciprocatory member engaging the said pitman, and means operatively connecting the body and the said reciprocatory member for throwing 110 the pitman past dead center at the ends of 120 its strokes.

3. In a device of the character described, a wheel mounted carriage including a driving crank, a rocking body mounted on the carriage, a pitman connecting the body and crank, a reciprocatory member, springs carried by the said member and engaging opposite portions of the pitman, and means operatively connecting the body and reciprocatory member for forcing the respective 125 130

- springs against the pitman at the ends of the strokes of the pitman.
4. In a device of the character described, a wheel mounted carriage including a driving crank, a rocking body carried by the carriage, a pitman connecting the body and crank, a tubular casing having slots through which the pitman passes, springs confined within the end portions of the casing and 10 engaging opposite portions of the pitman, and means operatively connecting the body and casing for pressing the respective springs against the pitman at the ends of the strokes of the pitman.
- 15 5. In a device of the character described, a wheel mounted carriage, including a driving crank, a rocking body mounted on the carriage, a pitman connecting the body and crank, a rocking shaft carried by the carriage and operatively connected with the body to rock therewith, and means operatively connecting the said shaft and the pitman to throw the pitman beyond dead center at the ends of its strokes.
- 20 6. In a device of the character described, a wheel mounted carriage including a driving crank, a rocking body mounted on the carriage, a pitman connecting the body and crank, a rocking shaft carried by the carriage and operatively connected with the body to rock therewith, said rocking shaft having a 25 crank, and a secondary pitman connected with the last mentioned crank and engaging the aforesaid pitman to throw the same beyond dead center at the ends of its strokes.
7. In a device of the character described, a wheel mounted carriage including a driving crank, a rocking body mounted on the carriage, a pitman connecting the body and crank, a rock shaft carried by the carriage and operatively connected with the body to rock therewith, the rock shaft having a 40 crank, a secondary pitman connected with the last mentioned crank, and springs carried by the secondary pitman and engaging opposite portions of the aforesaid pitman.
8. In a device of the character described, a wheel mounted carriage including a driving crank, a rocking body mounted on the carriage, a pitman connecting the body and crank, a rock shaft carried by the carriage and operatively connected with the body to rock therewith, the rock shaft having a 45 crank, a secondary pitman including a tubular, casing and a stem secured to one end thereof, the stem being connected with the last mentioned crank, and the casing having slots through which the first mentioned pitman passes, the first mentioned pitman having lugs directly above and below the said casing, and springs housed within the end portions of the casing and engaging opposite portions of the first mentioned pitman.
- 50 In testimony that I claim the foregoing 55 as my own, I have hereto affixed my signature in the presence of two witnesses.

BERT E. LAMKIN.
